UNITED STATES PATENT OFFICE.

WILLIAM SEWARD BAIRD, OF URBANA, ILLINOIS, ASSIGNOR TO ELECTRIC SCORE BOARD COMPANY, OF BOSTON, MASSACHUSETTS, A CORPORATION OF MASSACHUSETTS.

SCORE-BOARD OR THE LIKE.

1,102,218.

Specification of Letters Patent. Patented June 30, 1914.

Application filed November 21, 1910. Serial No. 593,422.

To all whom it may concern:

Be it known that I, WILLIAM SEWARD BAIRD, a citizen of the United States, residing at Urbana, in the county of Champaign 5 and State of Illinois, have invented certain new and useful Improvements in Score-Boards or the like, of which the following is a description.

My invention belongs to that general class 10 of devices known as score boards or the like, for use at base ball or other games for indicating or signaling to all portions of the field, or wherever the board may be positioned, the important points of the game, 15 such as for example the successive players, the balls, strikes, outs or such other information as may be desired.

In the drawings, the score board is shown 20 as applicable for base ball games, but it is obvious that with modifications it may be made applicable for other games, or for giving other signals or information, for example, it may be used with modifications in 25 theaters or other places, to indicate the program number being given, or for election returns, advertising purposes, etc.

The invention has among its objects the 30 production of a simple, convenient, accurate, efficient and more satisfactory device of the kind described that will not easily get out of repair, and which may be used wherever found applicable.

To this end my invention consists in the 35 novel construction, arrangement and combination of parts herein shown and described and more particularly pointed out in the claims.

In the drawings, wherein like reference 40 characters indicate like or corresponding parts, Figure 1 is a sectional view of the mechanism or motor for operating the indicators, the mechanism for one indicator being shown. Fig. 2 is a detailed sectional view taken substantially on line 2—2 of Fig. 45 1. Fig. 3 is a sectional view. Fig. 4 is a sectional view taken substantially on line 4—4 of Fig. 3. Fig. 5 is a view in elevation of catch mechanism between the ratchet wheels, taken substantially on line 5—5 of 50 Fig. 3. Fig. 6 is a front elevation of a portion of the score board and a diagrammatic representation of the operating mechanism

for one of the indicators, the wiring and the switch board.

Referring to the drawings, in which the 55 preferred form of device is shown as score board (Fig. 6), in which 1 represents the board of any suitable material and size provided with one or more dial faces. The board shown is applicable for a base ball 60 score board and is provided with dial faces 2—3—4—5 and 6, arranged to indicate balls, strikes, outs and the batters, etc., respectively. If desired, the board may be provided with dials for giving further information 65 and may be extended, for example, as partially shown at 9, on which any additional information may be put, as scores of other games not indicated on the dials, or advertisements, etc. Suitable characters 7, 70 etc., are arranged on the dial faces, the characters depending upon the use for which the board is to be put. As shown, the dials 2—3 and 4, for example, need only to be made of sufficient size to contain the information to 75 be given. The information is indicated by indicators or pointers 8, suitable mechanism or mechanical motors being employed for operating the indicators to advance the same or to return them to initial or the intermediate position, as desired. In use as a base ball score board, the board and dials are 80 preferably made comparatively large, so that the information may be conveyed to an observer at a considerable distance away. The 85 mechanism or motors for operating the indicators are similar for each dial, and may be controlled by suitable mechanisms from a distance, an electrical switchboard 70 being shown, which may be positioned where 90 convenient, or desired, and electrically connected with a mechanism.

In the drawings, the dial 2 is the only one shown provided with operating mechanism for the indicator 8, a description of the one 95 being sufficient for all. As shown, referring particularly to Figs. 1—5, the indicator 8 is secured to a rotatable shaft 10, arranged in suitable bearings 11, carried by the frame 12. The frame 12 may be supported in any 100 desired way, as shown it is carried by brackets 13 secured to the back of the score board 1, the shaft 10 projecting through to the face of the board. It is of course understood

that the well-known form of ball or roller bearings, or other anti-friction bearings (not shown) may be arranged between the shaft 10 and its bearings 11 or frame 12 if desired.

Suitably secured to the shaft 10 is a ratchet wheel 14, provided with teeth 15, which are preferably extended transversely as at 16. Any suitable means may be provided for rotating or driving the ratchet wheel 14 and shaft 10 to advance the indicator 8 in the desired direction, as shown clockwise. A very simple construction comprises a drum 18, secured to or formed integrally with the ratchet wheel, to which is secured a cord or chain 19, the free end of the cord being secured to a weight 20, or its equivalent. When the chain 19 is wound on the drum the weight 20 tends to 20 rotate the drum and wheel. The ratchet wheel 14, however, is normally prevented from rotating to advance the indicators by means of a pawl 21, or its equivalent, which may be operated in any suitable manner, 25 as shown by means of an electro-magnet 22, controlling the armature 21¹ on the pawl 21. The pawl 21 may be pivotally secured by a pin 25 to an extension 24 on the bracket 23, the bracket also serving to support the 30 magnet 22. When the pawl is raised the weight 20 tends to rotate the drum and unwind the chain 19 from the drum, at the same time rotating the ratchet wheel 14 until the next tooth 15 on the wheel is engaged by the pawl 21, assuming that the magnet 22 has become deenergized.

Loosely arranged on the shaft 10 is a ratchet wheel 26, provided with teeth 27, a drum 28, a cord or chain 29 and weight 40 30. The arrangement of the drum and chain is such that when the wheel is released, as hereinafter described, the same will be rotated in a reverse direction to that of the wheel 14 just described. Suitable means are provided on one of the 45 wheels for engagement with the other. In the construction shown the engaging means is carried by the wheel 26 and adapted to engage the teeth extensions 16 of the teeth 50 55 15 on the wheel 14. As shown, the wheel 26 is provided with extensions 31, which guide and support a dog or engaging member 32, which is normally out of engagement with, but adapted to engage the extended teeth 16 on the ratchet 14 when desired. The member 32 is preferably offset at 33 to pass the shaft 10, and is normally maintained out of engagement with any of the teeth extensions 16 by a resilient member 35 and coöoperating pin 36, a pin 34 limiting the movement of the member in 60 the opposite direction.

Any suitable means may be provided for operating the member 32, as shown a lever 65 38 pivotally carried by a pin 39 on the

wheel 36, is slotted as at 44, and engages the pin 43 on the member 32. As the free end of the lever 38 is drawn toward the shaft 10 it forces one end of the member 32 in the way of one of the teeth extensions 16 of the wheel 14. I preferably control or operate the lever 38 by means of an electro-magnet 41, carried by the bracket 42 on the wheel 26, arranged to coöperate with an armature 40 on the lever, the magnet being controlled as hereafter described. To counter balance the weight of the magnets 41 and the lever 38, a counterweight (w) may be provided on the wheel 26. Any suitable means, not shown, may be provided for winding the chain 29 on the drum 28 when the weight is run down. Wheel 26 is normally prevented from rotating by a pawl 46, arranged to engage one of the teeth 27, the pawl being provided with an armature 48 and the controlling magnet 49 carried by the bracket 50, the bracket being extended as at 51 and the pawl secured thereto by means of a pin 51¹ or its equivalent.

To prevent any accidental back-throw, or reverse rotation of the wheel 14, I provide a resilient catch 55, on a bracket 56, carried by the extension 31, the catch being adapted to engage the teeth 16 in notches 57. A resilient member 58 strengthens and maintains the catch 55 in operative position. (See Figs. 3 and 5). It is of course understood that any equivalent means may be provided for preventing the accidental back-throw or rotation mentioned.

The extended part 60 of the wheel 26 is provided with a commutator ring 61, suitably insulated therefrom by insulation 62, or its equivalent. The commutator ring 61 is electrically connected to one of the windings of the magnet 41, a hole or duct 63, through which the wire may pass on the interior of the drum 28, being provided. A brush 65 carried by a bracket 66 on the frame 12, but insulated therefrom, contacts with the commutator ring 61, the brush being suitably electrically connected with the switch or keyboard 70, as hereafter described.

Suitable binding posts 52 and 53, etc., may be provided for attaching the terminal wires from the electro-magnets. Any source of energy may be employed for controlling the electro-magnets, a battery 75 being shown for the purpose. A simple switch-board is shown in Fig. 6, in which figure I show a plurality of switch-bars or switches 71 and contacts 72-73 and 74, it being understood, however, that any other form of switchboard or switch mechanism may be employed. Referring to this figure, the contact 72 is electrically connected with a magnet 22, the return wire from the magnet being grounded or otherwise connected 130

with the battery. The switch 71 is connected to the battery. The contact 73 is electrically connected to the magnet 41, as described, through the brush and commutator 65-61, while the contact 74 is electrically connected to the magnet 49, it being understood that the magnets 41 and 49 are grounded through the mechanism, frame, etc., or otherwise connected to the opposite side of the battery, which is shown grounded on one side and connected to the switch-bar 71 on the other.

Assuming that it is desired to advance the indicator 8 to the character 1, the lever or switch 71 is moved to contact with the contact member 72, making a closed electrical circuit, as follows: battery 75, conductor 76, switch 71, contact 72, conductor 77, magnet 22, conductor 78, ground *g*, conductor 85 and the battery 75. This energizes the magnet 22 and raises the pawl 21, releasing the engaging tooth 15 so that the weight 20 rotates the wheel 14, thereby turning the shaft 10 and the indicator 8. As soon as the pawl 21 has been raised the switch 71 may be opened, breaking the circuit, so that the pawl 21 immediately drops and engages the next, or approaching tooth of the wheel 14, so that the indicator stops at 1. It might be noted that escapement mechanism, not shown, may be provided to prevent the wheel 14 from moving more than one tooth, or beyond the desired distance. In practice, however, this has been found unnecessary for either of the ratchet wheels, and is therefore not illustrated. It is of course understood that further operation of the switch 71 advances the indicator 8, for example as shown in the dotted lines 40 on dial 2 in Fig. 6. The indicator may be advanced as far as desired, as for example, in case where the dial is similar to 5 and 6, it may be continuously rotated. However, it is preferred to have the same so that it 45 may be returned either to initial or to an intermediate position when desired, without completely passing around the dial, regardless of the form of dial used. The operation of the mechanism to accomplish this is as follows: To retrieve or to return the indicator, the switch 71 is thrown to contact with 73, so that the member 32 is forced out to engage one of the teeth extensions 16 on the wheel 14. This circuit may be traced as follows: battery 75, conductor 76, switch 71, contact 73, conductor 79, brush 65, commutator 61, conductor 80, magnet 41, conductor 81, ground *g*, conductor 85 and the battery. As the arm or lever 38 is drawn toward the center, the member 32 is forced out, for example when the wheel is in position shown in Fig. 3, it is forced downward. The switch is then thrown farther to cover the contact 74, the circuit just described being still maintained closed. The newly

formed circuit may then be traced as follows: battery 75, conductor 76, switch 71, contact 74, conductor 83, magnet 49, conductor 84, ground, conductor 85 and the battery. This raises the pawl 46, releasing the engaged tooth 27, so that the weight 30 drives the wheel 26 in a reverse direction to the previous rotation of the wheel 14, the two, however, being connected through the member 32. The wheel 14 is therefore also rotated in a reverse direction. The wheel 14 is in this manner rotated or driven a sufficient distance to retrieve the indicator 8, as desired, to initial or to an intermediate position. The travel of the wheel 26 will of course be as desired, for example, if the indicator is at 3 on dial 2, it will be permitted to rotate sufficiently to return the indicator 8 to where desired. As soon as it is rotated the desired distance the switch-bar 71 is thrown to an open position so that the magnets 41 and 49 are deenergized, causing the pawl 46 to drop and engage one of the teeth 27, and permitting the member 32 to be retracted out of engaging position. It will be noted that the wheel 14 is engaged before the pawl 46 is raised. Broadly described, the mechanism or motor, consists of two rotatable members normally rotatable in opposite directions, provided with means for rotating the same and with means for normally preventing their rotation, and means for connecting the two as desired, so that one may be rotated or driven by the other in a reverse direction to its normal rotation.

From the description of the operation it will thus be seen that the indicators may be advanced or retrieved, as desired, that is either by advancing one, two, three or more points at intervals, or several points at a time, that they may be returned or retrieved in the same manner, either to the initial position or to any intermediate position, without passing completely around the dial. This is particularly convenient. For example, in the case of the dials 5 or 6, assuming that the indicator was at 1, indicating that No. 1 player was at bat, and that after his turn, No. 12 was called. In this case the indicator would be dropped back to 12. If it could not be so retrieved, it would be necessary to rotate it completely around the dial, or assuming that in operation the indicator was turned one point or character too far, it would be necessary to make a complete rotation to correct the error. As before mentioned, the mechanism is applicable for many uses, an illustration being its use in a theater to indicate the number on the program being given and the names of the players. As a further illustration, the dials might be arranged with characters from 1 to 10 or zero, each dial representing a numerical order, so that election returns might be indicated by operating the

several indicators. Numerous other examples might be mentioned or illustrated in the drawings showing different uses.

Having thus described my invention, it is obvious that various immaterial modifications may be made in the same without departing from the spirit of my invention, hence I do not wish to be understood as limiting myself to the exact form, arrangement, construction or combination of parts herein shown and described, or uses mentioned.

What I claim as new and desire to secure by Letters Patent is:—

1. A score board provided with characters on the face thereof arranged about a common center, an indicator arranged to co-operate with the characters on said face, and electrically controlled gravity operated means for advancing or retrieving said indicator comprising a rotatable shaft, a ratchet wheel secured thereon and provided with a suitable drum, a weight, a cable secured thereto and to said drum, a co-operating pawl for said ratchet wheel, controlling means for said pawl, and means for engaging and rotating said ratchet wheel in a direction opposite to its normal direction of rotation.

2. A score-board provided with a fixed dial having suitable characters thereon, a pointer arranged to co-operate with the characters on said dial, and means for operating said pointer, comprising a rotatable shaft, a ratchet wheel secured on said shaft, means for normally rotating said ratchet wheel, means for electrically controlling the rotation thereof, a rotatable member loosely arranged on said shaft and provided with means for engaging said wheel, and electrically controlled actuating means for said member.

3. A score board provided with a fixed dial face having a plurality of suitable characters thereon, a rotatable shaft, an indicator mounted thereon and arranged to co-operate with said characters, and electrically controlled means for actuating said indicator to advance the same or to return it to initial or an intermediate position comprising a pair of ratchet wheels, means for normally rotating the same in opposite directions, means for operatively connecting the two as desired, and means for normally preventing the rotation of said wheels.

4. A score board of the kind described provided with a plurality of fixed dials having suitable characters thereon, in combination with an indicator for each dial, means for normally preventing the actuation of any of said indicators, means for actuating any of said indicators in either direction independently of the others, and electrically operated means for independently controlling said actuating means.

5. A score board of the kind described

provided with a plurality of fixed dials thereon, each marked for identification and provided with suitable characters for indicating variable information, an indicator for each dial and movable thereabout arranged to co-operate with the characters on its respective dial, in combination with electrically controlled gravity operated actuating means for independently advancing any of said indicators, a substantially similarly formed mechanism for reversing said actuating means and retrieving same as desired.

6. A score board of the kind described provided with a plurality of fixed dials thereon and with indicators arranged to move about said dials, in combination with gravity operated means for advancing said indicators as desired, electrically controlled means for normally preventing the advancement thereof, gravity operated means for retrieving said indicators as desired including electrically operated engaging means between said advancing and retrieving means, and electrically controlled means for normally preventing the retrieving thereof.

7. In a device of the kind described, a dial, an indicator movable about said dial, means for operating said indicator, comprising a rotatable member and gravity operating means for actuating the same, means for normally preventing the actuation of said member, and means for actuating said member in the opposite direction as desired including electrically controlled clutch mechanism.

8. In a device of the kind described and in combination, a dial provided with suitable characters thereon, a movable indicator arranged to co-operate with said dial, and electrically controlled means for actuating said indicator to advance the same or to return it to initial or intermediate position, said means comprising a rotatable member and means for rotating same, electrically controlled means for normally controlling the rotation thereof, a rotatable driving member and means tending to normally rotate the same in a direction opposite to the rotation of said first mentioned member, electrically controlled means for normally controlling the rotation of said last mentioned member, and electrically controlled means for connecting said members together during the rotation of said driving members.

9. In a device of the kind described and in combination, a dial provided with suitable characters thereon, a movable indicator arranged to co-operate with said dial and electrically controlled means for actuating said indicator to advance the same or to return it to initial or intermediate position, said means comprising a rotatable member and means for rotating the same, electrically controlled means for normally pre-

venting the rotation thereof, a rotatable driving member and means tending to normally rotate the same in a direction opposite to the rotation of said first mentioned member, electrically controlled means carried by one of said members and arranged to operatively engage the other member.

10. In a device of the kind described, a score board provided with a dial on the face thereof, said dial having suitable characters thereon, an indicator arranged to cooperate with the characters on said dial and electrically controlled means for advancing said indicator or returning same toward the initial position, comprising a pair of members rotatably mounted on a common shaft, means for rotating said members in opposite directions, one of said members connected with said indicator, electrically controlled means for normally preventing the rotation of said member, electrically controlled means for normally preventing the rotation of the other of the said members, means for connecting said members and electrically controlled means for actuating said connecting means.

11. In a device of the kind described, a score board provided with a dial on the face thereof, said dial having suitable characters thereon, an indicator arranged to cooperate with the characters of said dial, and means arranged on the back of said board for advancing said indicator or returning same toward the initial position, comprising a pair of members rotatably mounted on a common shaft, means for rotating said members in opposite directions, one of said members connected with said indicator, means for normally preventing the rotation of said member, means for normally preventing the rotation of the other of the said members, means for connecting said members and means for actuating said connecting means.

12. In a device of the kind described and in combination, a score board provided with a dial face thereon, an indicator movable over said face, and electrically controlled means for actuating said indicator, said means comprising a driven member connected with the indicator, means for rotating said member to advance said indicator, electrically controlled means for normally

preventing the rotation of said member, and means for rotating said driven member in a reverse direction when desired, comprising a driving member therefor normally rotatable in a reverse direction relative thereto, means normally out of engagement for operatively connecting said driving and said driven members when desired, and electrically controlled means for normally preventing the operation of said driving member.

13. In a device of the kind described and in combination with suitable indicating mechanism, a pair of members rotatably mounted upon a common shaft, electrically controlled means for normally preventing the rotation of said members, means for rotating said members in opposite directions when released, means carried by one of said members for engaging the other, and electrically controlled means for operating said engaging means.

14. In a score board of the kind described and in combination, a dial, an indicator rotatable thereon, actuating means for said indicator comprising a motor consisting of two members arranged on a common shaft and normally rotatable in opposite directions, said members provided with means for engaging each other, electrically controlled means for operating said engaging means, and electrically controlled means for controlling the operation of said members as desired.

15. In a device of the kind described and in combination with indicating mechanism, controlling mechanism for said indicating mechanism comprising, a motor consisting of two rotatable members normally rotatable in opposite directions, and provided with means for rotating the same, means for normally preventing the rotation of said members, and means for connecting the two as desired, so that one is rotated by the other in a direction the reverse of its normal rotation.

In testimony whereof, I have hereunto signed my name in the presence of two subscribing witnesses.

WILLIAM SEWARD BAIRD.
